[57] **CLAIM**

The ornamental design for a pull-apart sheath introducer for percutaneous catheter introduction, as shown and described.

DESCRIPTION

FIG. 1 is a front perspective view of a pull-apart sheath introducer for percutaneous catheter introduction, showing my new design;

FIG. 2 is an enlarged front elevational view thereof, the rear elevational view being identical thereto;

FIG. 3 is a side elevational view thereof, the opposite side being identical thereto;

FIG. 4 is a top plan view thereof; and

FIG. 5 is a bottom plan view thereof.

FIG.1

FIG.2

FIG.3

FIG.4
